ENGINE STARTER

James A. Charter, Chicago, Ill., assignor to
 Charter Drive, Inc., Chicago, Ill., a corpora-
 tion of Illinois

Application May 29, 1936, Serial No. 82,428

12 Claims. (Cl. 74—9)

This invention relates generally to engine starters and more particularly to starters adapted for use with internal combustion engines and the like.

5 It is an important object of the present invention to provide an engine starter of the type employing a longitudinally shiftable pinion on a drive shaft unit and a yieldable driving connection interposed therebetween wherein the pinion is prevented from rebounding toward the engine gear after said pinion has been shifted to its "out" or retracted position.

10 The invention contemplates preventing the rebounding of the driving pinion in a starter of the type wherein a tracker carried by the drive shaft unit moves within the convolutions of a coiled spring shiftable as a unit with said pinion.

15 It is a further object of the present invention to secure the driving pinion against rebounding without the use of auxiliary braking or holding devices, and to this end I propose to render the tracker and coiled spring mentioned above frictionally cooperative after the pinion has been shifted to its retracted position for preventing the inadvertent movement or rebounding of the pinion toward the engine gear.

20 More specifically my invention contemplates using the starter elements which form the driving connection between the pinion and the drive shaft unit, as for example the above mentioned spring and tracker, to automatically set up sufficient frictional resistance as the pinion reaches its limiting position of retraction. To accomplish this I cause said tracker and spring to experience relative axial movement as an incident to the retraction of the pinion and thereby establish sufficient frictional contact to prevent rebounding of the pinion and at the same time permit the pinion to automatically shift toward the engine gear when the drive shaft unit is subsequently rotated by the starting motor.

25 The foregoing and numerous other objects and advantages will be more apparent from the following detailed description when considered in connection with the accompanying drawing, wherein:

30 Figure 1 is a side elevational view of an engine starter constructed in accordance with the teachings of the present invention and disclosing the driving pinion in its retracted or "out" position, the "in" position of the pinion being indicated by dot and dash lines;

35 Figure 2 is a side elevational view of the engine starter, disclosing the pinion shifted to its "in" 55 or driving position;

Figure 3 is a central longitudinal sectional view taken substantially along the line 3—3 of Figure 1;

Figure 4 is a transverse sectional view taken substantially along the line 4—4 of Figure 1; 5

Figure 5 is a fragmentary central sectional view of a slightly modified starter construction employing a coiled spring which normally urges the pinion structure axially of the drive shaft 10 unit.

Referring now to the drawing more in detail, wherein like numerals have been employed to designate similar parts throughout the various figures, it will be seen that one embodiment of 15 my invention contemplates an engine starter, designated generally by the numeral 10, which includes a rotary driving structure, designated generally by the numeral 12. This rotary driving structure comprises a driving pinion proper, 20 14, and an enlarged sleeve section or drum 16 formed integral with said pinion.

A driving spring structure 18 of a multiple or double strand construction is coupled with the sleeve section 16 through the agency of hook 25 portions 20 diametrically positioned and provided at the free extremities of the spring strands. These hook portions 20 are adapted to be received by complementary recesses 22 formed in the sleeve section 16. Each recess includes an 30 axially extending portion and a circumferentially extending portion to accommodate the complementary hook 20.

The pinion and spring structure just described is mounted upon a drive shaft unit which I have 35 indicated generally by the numeral 24. This drive shaft unit in the present embodiment includes a motor shaft 26 which connects with a suitable electric starting motor (not shown). The drive shaft unit 24 also includes a sleeve section 40 28 which is driven with the motor shaft 26 through the agency of a suitable key and key-way construction 30, Figure 3. A radially extending actuating member or tracker 32 is carried by the sleeve 28 and extends within the helical way 45 33 in the spring structure 18. A second sleeve section 34 is drivingly coupled at 35 with the sleeve section 28. This sleeve section 34 provides a support for the pinion sleeve section 16. 50 The sleeve 16 is adapted to shift longitudinally of the sleeve section 34 when the tracker 32 moves within the helical way 33. To prevent longitudinal movement of the sleeve section 28 with respect to the shaft 26, a suitable set screw 55

36 is provided, which is secured against loosening by means of a resilient ring 38.

From the foregoing it will be apparent that if the starter mechanism just described occupies the position shown in Figure 1 and the drive shaft unit 24 suddenly experiences rotation in a counter-clockwise direction as viewed from the left of Figure 1, due to the activation of the starting motor (not shown), the spring structure 18, together with the pinion structure 14, will be shifted without rotation to the right. This carries the pinion 14 into mesh with the engine gear 40 to be started. In other words, the tracker 32 in making one complete revolution cooperates with the helical spring 18 so as to shift the pinion 14 from its "out" position, shown in Figure 1, to its "in" or meshing position, shown in Figure 2. At this point the tracker engages the closed extremity 42 of the spring 18 and continued rotation of the drive shaft unit causes the pinion 14 to impart rotation to the gear 40.

As soon as the internal combustion engine (not shown) becomes self-actuated, the speed of rotation of the gear 40 exceeds the normal rotative speed of the pinion 14, thereby causing said pinion and the spring structure 18 connected therewith to experience movement to the left. As the pinion 14 and its associated elements approach the limit of its retracting movement, the frictional engagement of the tracker 32 with the side of the spring strand positioned immediately to the left of the tracker, Figure 1, is increased. In other words, further continued rotation of the pinion 14 is retarded due to this building up of frictional resistance between the tracker and the spring. This frictional engagement between the tracker and the spring causes a gradual deceleration of the pinion 14, or, in other words, gradually dissipates the kinetic energy stored up within the rotating pinion. Should this kinetic energy be dissipated by causing the pinion movement to be suddenly arrested, as by means of a fixed abutment, the pinion would experience a rebound which would have a tendency to move it into clashing engagement with the rotating gear 40.

Attention is directed to a lug 44 secured to the inner wall of the pinion sleeve section 16. As the pinion is rotated so as to cause it to move to the left, and the lug 44 reaches the position indicated by the dot and dash lines of said lug in Figure 4, it engages the end abutment surface or section of the sleeve 34 and therefore the tracker 32 and associated spring surface begin to build up an increase in frictional resistance. This building up of frictional resistance continues until the lug 44 reaches the vicinity indicated by the solid line disclosure of the lug in Figure 4. When the lug reaches this vicinity, the frictional resistance which has been developed is sufficient to completely retard the rotative effect of the pinion and to prevent said pinion from rebounding toward the engine gear 40. To positively prevent building up frictional resistance beyond a desired amount, I provide a shoulder or abutment surface 46 on the sleeve section 34. Thus if there is a slight tendency for the lug 44 to continue to move beyond the solid line position shown in Figure 4, the abutment surface 46 will positively prevent such movement.

I have so designed by improved starter as to build up just enough frictional resistance between the tracker and the spring to dissipate the kinetic energy of the retracting pinion 14 so as to prevent rebounding of said pinion, but not enough frictional resistance to prevent the free forward

movement of the pinion when the starting motor is again activated.

In some instances it may be desirable to employ a coil spring 48, shown in Figure 5. This coil spring serves to insure frictional contact between the companion surfaces of the spring and tracker when the pinion approaches the limit of its rearward or retracting movement. This spring 48 need act only through a limited range of the axial movement of the pinion, namely, the movement experienced by the pinion as it approaches its final position of retraction. To prevent creeping of the pinion toward the starting motor, resulting from vibrations of the vehicle with which the starter may be connected, etc., I provide an annular wire spring 50 which resiliently rests within a companion peripheral recess in the sleeve section 16. One extremity of this annular spring 50 is bent inwardly to provide an inwardly extending finger 52. The inner or free extremity of this finger 52 is adapted to be positioned within an annular recess 54 in the sleeve section 34 when the pinion occupies its position of retraction as shown in Figures 1 and 3. The resistance to axial movement to the right set up by the resilient finger 52 is sufficient to prevent inadvertent movement or creeping of the pinion into engagement with the engine gear 40, but is insufficient to prevent the advancement of the pinion, when the starting motor is actuated, to rotate the drive shaft unit 24. In other words, the finger 52 merely serves as an "anti-creep" device.

From the foregoing it will be apparent that my invention contemplates an engine starter in which no auxiliary mechanism or actuating elements are required to prevent rebounding of the pinion. I have obviated the necessity of using overrunning clutches or brake mechanisms by so designing my starter as to insure frictional engagement between the actuating parts thereof, as, for example, between the actuating means or member 32 and the spring structure 18, and thereby dissipate the kinetic energy of the pinion during its retraction sufficiently gradual to prevent rebounding of the pinion. Thus my invention contemplates a starter which completely obviates the difficulties resulting from the rebounding of the pinion by employing a very simple arrangement of parts which are few in number and durable in construction. Attention is also directed to the fact that I am able to facilitate the cushioning effect of the spring 18 by having the convolutions thereof immediately adjacent the pinion sleeve section 16 positioned close together. Inasmuch as only one complete revolution of the tracker is required to shift the driving pinion between its "in" and "out" positions, the remaining portion of the spring strands are not required to provide a helical way for the tracker. Hence these remaining portions of the spring strands are positioned closer together and thus facilitate the cushioning effect of the spring. Any tendency for the pinion to clash with the teeth of the engine gear 40 is cushioned by the spring, and furthermore the arrangement of the spring is such as to enhance the yieldable driving characteristics thereof.

Obviously the invention is not limited to the arrangement disclosed herein but is capable of other modifications and changes without departing from the spirit and scope of the invention as set forth in the appended claims.

Having thus described the invention, what I claim as new and desire to secure by Letters Patent is:

1. The method of controlling the starting of an internal combustion engine which includes the steps of relatively rotating a pair of frictionally engageable actuating members so as to cause movement of a driving member into operative association with an engine part to be driven, subsequently causing relative rotary movement of said actuating members so as to quickly retract said driving member, and when said driving member approaches a predetermined position of retraction, gradually building up frictional resistance between said actuating members to gradually decelerate said engine driving member and prevent the rebounding thereof.

15 2. The method of controlling the starting of an internal combustion engine which includes the steps of relatively rotating a pair of frictionally engageable actuating members so as to cause movement of a driving member into operative association with an engine part to be driven, subsequently causing relative rotary movement of said actuating members so as to quickly retract said driving member, and when said driving member approaches a predetermined position of retraction, urging a surface of at least one of said actuating members axially and rotatably toward a surface of the other actuating member to gradually build up frictional resistance between said actuating members whereby to gradually decelerate said engine driving member and prevent the rebounding thereof.

20 3. The method of controlling the starting of an internal combustion engine which includes the steps of relatively rotating a pair of frictionally engageable actuating members, one of which provides a helical path, so as to cause movement of a driving member into operative association with an engine part to be driven, subsequently causing relative rotary movement of said actuating members so as to quickly retract said driving member, and when said driving member approaches a predetermined position of retraction gradually building up frictional resistance between said actuating members to gradually decelerate said engine driving member and prevent the rebounding thereof.

25 4. In an engine starting device, a drive shaft unit, an engine driving member on said unit adapted for both longitudinal and rotary movement, said member being adapted in one shifted position to operatively engage an engine gear to be driven, a coiled spring structure on said unit and movable with said driving member, actuating means movable with said drive shaft unit and cooperating with said coiled spring for effecting longitudinal movement of said engine driving member, an abutment section movable with said driving member, and a second abutment section associated with said drive shaft unit adapted to be frictionally engaged by the first abutment section when said driving member is being retracted whereby to cause relative gradual building up of frictional resistance between said coiled spring and actuating means during the final relative rotation between said coiled spring and actuating means, and thereby gradually decelerate said engine driving member so as to prevent rebounding thereof.

30 5. In an engine starting device, a drive shaft unit, an engine driving member on said unit adapted for both longitudinal and rotary movement, said member including an axially extending portion providing a housing and adapted in one shifted position to operatively engage an engine gear to be driven, a coiled spring structure

35 6. In an engine starting device, a drive shaft unit, an engine driving member on said unit adapted for both longitudinal and rotary movement, said member including an axially extending portion providing a housing and adapted in one shifted position to operatively engage an engine gear to be driven, a coiled spring structure on said unit and movable with said driving member, actuating means movable with said drive shaft unit and cooperating with said coiled spring for effecting longitudinal movement of said engine driving member, an abutment section movable with said driving member, and a second abutment section associated with said drive shaft unit adapted to be frictionally engaged by the first abutment section when said driving member is being retracted whereby to cause relative gradual building up of frictional resistance between said coiled spring and actuating means during the final relative rotation between said coiled spring and actuating means, and thereby gradually decelerate said engine driving member so as to prevent rebounding thereof.

40 7. In an engine starting device, a drive shaft unit, an engine driving member on said unit adapted for both longitudinal and rotary movement, said member being adapted in one shifted position to operatively engage an engine gear to be driven, a coiled spring structure on said unit and movable with said driving member, actuating means movable with said drive shaft unit and cooperating with said coiled spring for effecting longitudinal movement of said engine driving member, an abutment section movable with said driving member, a second abutment section associated with said drive shaft unit adapted to be frictionally engaged by the first abutment section when said driving member is being retracted whereby to cause relative gradual building up of frictional resistance between said coiled spring and actuating means during the final relative rotation between said coiled spring and actuating means, and thereby gradually decelerate said engine driving member so as to prevent rebounding thereof, said abutment sections being positioned within said housing.

45 8. In an engine starting device, a drive shaft unit, an engine driving member on said unit adapted for both longitudinal and rotary movement, said member being adapted in one shifted position to operatively engage an engine gear to be driven, a coiled spring structure on said unit and movable with said driving member, actuating means movable with said drive shaft unit and cooperating with said coiled spring for effecting longitudinal movement of said engine driving member, an abutment section movable with said driving member, a second abutment section associated with said drive shaft unit adapted to be frictionally engaged by the first abutment section when said driving member is being retracted whereby to cause relative gradual building up of frictional resistance between said coiled spring and actuating means during the final relative rotation between said coiled spring and actuating means, and thereby gradually decelerate said engine driving member so as to prevent rebounding thereof, and resilient means acting between the structure of said drive shaft unit and engine driving member to maintain frictional contact between said actuating means and spring.

50 9. In an engine starting device, a drive shaft unit including a motor shaft and interlocked sleeve elements, an engine driving member on said unit adapted for both longitudinal and rotary movement, said member being adapted in one shifted position to operatively engage an engine gear to be driven, a coiled spring structure

55 10 11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100

on said unit and movable with said driving member, actuating means movable with said drive shaft unit and cooperating with said coiled spring for effecting longitudinal movement of said engine driving member, an abutment section movable with said driving member, and a second abutment section associated with said drive shaft unit adapted to be frictionally engaged by the first abutment section when said driving member is being retracted whereby to cause relative gradual building up of frictional resistance between said coiled spring and actuating means, and thereby gradually decelerate said engine driving member so as to prevent rebounding thereof.

9. In an engine starting device, a drive shaft unit, an engine driving member on said unit adapted for both longitudinal and rotary movement, said member being adapted in one shifted position to operatively engage an engine gear to be driven, a coiled spring structure on said unit and movable with said driving member, said coiled spring structure including a double strand 25 of wire providing a loop at one extremity, the opposite free extremities of said strands being coupled with said engine driving member, actuating means movable with said drive shaft unit and cooperating with said coiled spring for effecting longitudinal movement of said engine driving member, an abutment section movable with said driving member, and a second abutment section associated with said drive shaft unit adapted to be frictionally engaged by the first 30 abutment section when said driving member is being retracted whereby to cause relative gradual building up of frictional resistance between said coiled spring and actuating means during the final relative rotation between said coiled spring 35 and actuating means, and thereby gradually decelerate said engine driving member so as to prevent rebound thereof.

10. In an engine starting device, a drive shaft unit, an engine driving member on said unit adapted for both longitudinal and rotary movement, said member being adapted in one shifted position to operatively engage an engine gear to be driven, a coiled spring structure on said unit and movable with said driving member, actuating 40 means movable with said drive shaft unit and cooperating with said coiled spring for effecting longitudinal movement of said engine driving member, an abutment section movable with said driving member, a second abutment section associated with said drive shaft unit adapted to be frictionally engaged by the first abutment section 45 when said driving member is being retracted whereby to cause relative gradual building up of frictional resistance between said coiled spring

and actuating means during the final relative rotation between said coiled spring and actuating means, and thereby gradually decelerate said engine driving member so as to prevent rebounding thereof, and means for positively limiting the 5 retracting rotation of the engine driving member.

11. In an engine starting device, a drive shaft unit, an engine driving member on said unit adapted for both longitudinal and rotary movement, said member being adapted in one shifted 10 position to operatively engage an engine gear to be driven, a coiled spring structure on said unit and movable with said driving member, actuating means movable with said drive shaft unit and cooperating with said coiled spring for effecting 15 longitudinal movement of said engine driving member, an abutment section movable with said driving member, a second abutment section associated with said drive shaft unit adapted to be frictionally engaged by the first abutment section 20 when said driving member is being retracted whereby to cause relative gradual building up of frictional resistance between said coiled spring and actuating means during the final relative rotation between said coiled spring and actuating 25 means, and thereby gradually decelerate said engine driving member so as to prevent rebounding thereof, and means for limiting the amount of 30 rotary frictional resistance which may be built up between said spring and actuating means.

12. In an engine starting device, a drive shaft unit, an engine driving member on said unit adapted for both longitudinal and rotary movement, said member being adapted in one shifted position to operatively engage an engine gear to 35 be driven, a coiled spring structure on said unit and movable with said driving member, actuating means movable with said drive shaft unit and cooperating with said coiled spring for effecting 40 longitudinal movement of said engine driving member, an abutment section movable with said driving member and having an abutment surface positioned in a plane substantially perpendicular to the axis of said driving member, and a second abutment section associated with said drive shaft 45 unit having an abutment surface lying in a plane substantially perpendicular to the axis of said driving member and adapted to be frictionally engaged by the surface of said first abutment section when said driving member is being retracted whereby to cause relative gradual building 50 up of frictional resistance between said coiled spring and actuating means during the final relative rotation between said coiled spring and actuating means, and thereby gradually decelerate 55 said engine driving member so as to prevent rebounding thereof.

JAMES A. CHARTER.
